UNITED STATES PATENT OFFICE.

THEODORE SCHULZE, OF NEW YORK, N. Y.

TOOL FOR HOLDING PIPE-NIPPLES.

SPECIFICATION forming part of Letters Patent No. 570,233, dated October 27, 1896.

Application filed February 20, 1896. Serial No. 580,001. (No model.)

To all whom it may concern:

Be it known that I, THEODORE SCHULZE, of New York city, New York, have invented an Improved Tool for Holding Pipe-Nipples, 5 of which the following is a specification.

This invention relates to a tool of simple construction for holding pipe-nipples while a thread is being cut upon them.

In the accompanying drawings, Figure 1 is 10 a side view, partly in section, of my improved pipe-holding tool. Fig. 2 is an end view thereof.

My improved tool is composed of a squared stem *a*, which is enlarged at one or both ends 15 to form the cylindrical head or heads *a'*, which are made integral with the stem. Each head is provided with a threaded socket adapted to engage the threaded end of a gas-pipe *A*. If two heads *a'* are formed on the stem, the 20 sockets should be of different diameters, so as to fit differently-sized pipes. Within each socket there is contained a threaded plug *b*, which is adapted to engage the thread of the socket and which is screwed down so as to 25 leave the length of the remaining opening equal about to the length of the threaded section of the pipe-nipple. The outer end of the plug *b* is provided with a central horn *b'*, having a pointed end and a cylindrical body 30 which is adapted to extend into and engage the inner side of the nipple. Around this horn is formed upon the plug an annular seat *b²*, equal in width to the thickness of pipe to be cut.

In use the pipe *A* is screwed into the proper 35 head *a'*, and then the squared stem *a* is clamped between the jaws of a vise, so that it will not turn. The exposed end of the pipe *A* is now attacked by the stock and die and a thread is cut upon it in the usual manner. 40 During this operation the guide of the die will be centered upon and gradually move over the head *a'*, such head being made of a diameter to snugly fit into the bore of the guide. While the thread is thus cut upon the outer 45 end of the pipe, its inner end will be so held that it cannot revolve and also that its thread cannot become injured.

It will be seen that with my tool threads can be quickly and conveniently cut upon 50 any lengths of pipes and that the tool when forming part of a plumber's outfit will greatly simplify his labors.

What I claim is—

A tool for holding pipe-nipples composed 55 of a squared stem, an integral cylindrical head having a threaded socket, and a plug having a threaded body that engages the threaded socket, said plug being provided with an annular pipe-seat and with a cylindrical horn that is adapted to engage the bore 60 of the nipple, substantially as specified.

THEODORE SCHULZE.
